BATTERY CONNECTOR

Jack P. Whitaker, Kansas City, Mo., assignor to
 Whitaker Cable Corporation, North Kansas
 City, Mo., a corporation of Delaware

Application June 18, 1945, Serial No. 600,152

5 Claims. (Cl. 173—259)

1

This invention relates to electric current conductors of the character usually employed to interconnect storage batteries and of the type having a sharpened pin to pierce the metal posts of the said batteries.

The primary aim of this invention is to provide a battery connector of the afore-mentioned type wherein the sharpened pin is especially mounted in a molded body with the conductor joined directly thereto in a novel and unique manner insuring the continued and rough use of the connector assembly without accidentally disconnecting the said conductor and pin and in some instances rendering more secure the joint between the pin and conductor.

Minor objects of the invention will appear during the course of the following specification referring to the accompanying drawing, wherein:

Fig. 1 is a side elevational view of a battery connector made in accordance with the present invention.

Fig. 2 is an enlarged central sectional view through the connector shown in Fig. 1.

Fig. 3 is a sectional view taken on line III—III of Fig. 2.

Fig. 4 is a perspective view of the upper portion of the pin forming a part of a connector made in accordance with the modified form of the invention.

Fig. 5 is a similar view illustrating the manner of joining the conductor to the bifurcated pin.

Fig. 6 is a sectional view through the body of the connector with that form of pin and conductor illustrated in Figs. 4 and 5 in the operative position, and

Fig. 7 is a central sectional view through a battery connector illustrating a pin and conductor connection of a form that embodies a still further modification of my invention.

Connectors of the type having sharpened pins and molded bodies have heretofore been employed with the result that the connection between the conductor and said pin becomes loosened through long and continued hard use. The manner of joining a length of wire or conducting material 10 to the pointed pin 12 has heretofore been unsatisfactory and susceptible to parting during use. When the battery connector assembly is moved to place and pin 12 is forced into the post of a battery, not here shown, body 14 is customarily struck by a hammer to drive pin 12 securely into its operative position. Such blows often times jar the connection between conductor 10 and pin 12 to a point where current will not flow, oxidation occurs and the connector is thereby rendered useless.

In producing the connector embodying the form of invention illustrated in Figs. 1, 2 and 3, pin 12 is flattened to form a head 16 at one end and conductor 10 is rebent upon itself and flat-

tened by spreading the strands thereof. The hook 18 so formed on the end of conductor 10 is caused to embrace head 16 whereupon a spot weld 20 is used to affix conductor 10 to head 16. After such step is taken, molded body 14 is cast around head 16 of pin 12 to maintain hook 18 in place. A striking face 22 forms a part of body 14 and after the operator has pressed pin 12 into the battery post as far as possible through the employment of his hands, a hammer or other instrument is brought into play and surface 22 is struck to tighten the pin and to insure a good electrical connection.

Conductor 10 is provided with conventional insulation 24 and before the conductor 10 is shaped to form hook 18, the insulation 24 is removed from a portion of conductor 10 at the end thereof. Body 14 embraces a short length of insulation 24, as clearly shown in Figs. 2 and 3, and therefore, a relatively rigid assembly comprising pin 12, conductor 10, body 14 and insulation 24, is the result.

The striking of body 14 often times proves detrimental to the assembly and it is desired to employ the force applied by tools or the like, to strengthen the bond between conductor 10 and pin 12 rather than loosen the same. The form of the invention illustrated in Figs. 4, 5 and 6 is therefore, advantageous in employing the force exerted upon striking face 50 of body 52. Pin 54 is bifurcated or slotted longitudinally as at 56 to present a pair of fingers 58, one of which is extended into a cap 60, the free end whereof is flanged as at 62 to engage the inclined surface 64 of one of fingers 58. When cap 60 is formed as illustrated in Figs. 5 and 6, its upper surface is adjacent to striking face 50 on body 52. One end of conductor 66 is rebent upon itself to form a hook which embraces one of fingers 58 and its bight lies in slot 56 between fingers 58. When flange 62 of cap 60 rides along inclined face 64 of finger 58, the hooked portion of conductor 66 is clamped tightly in slot 56.

When the assembly is originally produced in the factory, the material from which body 52 is cast will flow into slot 56 to hold conductor 66 in place, but as body 52 becomes deformed, due to use, the cap 60 will progressively tighten finger 58.

In Fig. 7, the battery connector assembly illustrated comprises a conductor 100 having insulation 102 and a hook portion 104. Pin 106 has a head 108 provided thereon, which head is bifurcated to present fingers 110 between which slot 112 is disposed. Cap 114 is flanged to present a cup-shaped body into which fingers 110 project. The inclined sides 116 of fingers 110 engage the flange of cap 114 to the end that blows received by striking face 118, may be transmitted to fingers 110 to draw the same together as the device is used. Thus hook 108 will be more tightly en-

gaged and when body 120 is deformed, the connection between conductor 100 and pin 106 will not be threatened.

Having thus described my invention what I claim as new and desire to obtain by Letters Patent is:

1. A battery connector of the type set forth comprising a sharpened pin having a head formed thereon at one end; a conductor rebent upon itself at one end thereof to form a hook for embracing the head; and a molded body of lead cast around the head of the pin and the hook on the conductor, said head being bifurcated and provided with means for closing the bifurcation as force is applied thereto during the driving of the pin into operative position in a battery post or the like, the hook of the conductor being threaded through the bifurcation to be clamped thereby as the bifurcation is closed.

2. A battery connector of the type set forth comprising a sharpened pin having a head formed thereon at one end; a conductor rebent upon itself at one end thereof to form a hook for embracing the head; and a molded body of lead cast around the head of the pin and the hook on the conductor, said head being split longitudinally to present a pair of fingers, the hooked portion of the conductor being confined within the split and embracing one of the fingers, said head having a cap overlying the upper end thereof and adjacent to the upper end of the molded body, the said cap and the head being formed to draw the fingers together as force is applied to the cap.

3. A battery connector of the type set forth comprising a sharpened pin having a head formed thereon at one end; a conductor rebent upon itself at one end thereof to form a hook for embracing the head; and a molded body of lead cast around the head of the pin and the hook on the conductor, said head being split longitudinally to present a pair of fingers, the hooked portion of the conductor being confined within the split and embracing one of the fingers, said head having a cap overlying the upper end thereof and adjacent to the upper end of the molded body, the said cap and the head being formed to draw the fingers together as force is applied to the cap, the said body having a striking face provided thereon adjacent to the said cap.

4. A battery connector of the type set forth comprising a sharpened pin having a head formed thereon at one end; a conductor rebent upon itself at one end thereof to form a hook for embracing the head; and a molded body of lead cast around the head of the pin and the hook on the conductor, said head being split longitudinally to present a pair of fingers, the hooked portion of the conductor being confined within the split and embracing one of the fingers, said head having a cap overlying the upper end thereof and adjacent to the upper end of the molded body, the said cap and the head being formed to draw the fingers together as force is applied to the cap, one of said fingers being extended to form said cap and having a flange portion thereon engageable with the other finger.

5. A battery connector of the type set forth comprising a sharpened pin having a head formed thereon at one end; a conductor rebent upon itself at one end thereof to form a hook for embracing the head; and a molded body of lead cast around the head of the pin and the hook on the conductor, said head being split longitudinally to present a pair of fingers, the hooked portion of the conductor being confined within the split and embracing one of the fingers, said head having a cap overlying the upper end thereof and adjacent to the upper end of the molded body, the said cap and the head being formed to draw the fingers together as force is applied to the cap, the outermost faces of said fingers converging as the free ends thereof are approached, said cap being a cup-shaped member disposed in encircling relation with said fingers.
